[57] CLAIM

The ornamental design for a racquetball trophy, as
shown and described.

DESCRIPTION

FIG. 1 is a front elevational view of a racquetball tro-
phy showing my new design;

FIG. 2 is a left side elevational view thereof;

FIG. 3 is a top plan of the figure alone with the square

base removed and the figure rotated clockwise 45°; and
FIG. 4 is a bottom plan view thereof.

FIG. 1

FIG. 2

FIG. 3

FIG. 4
